UNITED STATES PATENT OFFICE

WILLIAM F. HAUPT, OF ORANGE, NEW JERSEY, ASSIGNOR TO THE BATES MANUFACTURING COMPANY, OF WEST ORANGE, NEW JERSEY, A CORPORATION OF NEW JERSEY

NUMBERING MACHINE

Application filed January 4, 1928. Serial No. 244,397.

My invention relates to numbering machines and particularly to that class of numbering machines which are automatic in their action and which are usually so made that they permit the user to print numbers consecutively, or to print each number several times before the machine automatically changes one or more of the numbering or type wheels to effect the printing of the next higher number upon the next operation thereof, or to repeat the printing of the same number over and over again.

The machine shown and described herein as a preferred embodiment of my invention, is constructed and arranged so that it may be set to repeat, to print consecutively, and to duplicate,—the machine thus having three different "index settings" and being what is commonly known as a "three-movement" machine. My invention, however, is subject to variation in the direction just noted, although it is especially designed for application to machines having but a small range of settings such as to a three or four-movement machine.

The present invention is especially designed for application to numbering machines of the type disclosed in my pending application Serial No. 174,298, filed March 10, 1927, and in some aspects is an improvement on the invention described and claimed in such application.

One of the objects of my invention is to provide in a numbering machine, an improved control mechanism for the working pawl or equivalent device, which while quite similar in principle and operation to the control mechanism disclosed in my said pending application, has fewer parts of simpler construction and is also preferably adapted to be adjusted or indexed directly to thereby change the machine to any desired setting.

Another object of my invention is to provide in a machine of the character described, simple and novel means for effectively operating the working pawl, or equivalent device, which actuates or advances the numbering or type wheels; such means preferably comprising an oscillatory member constituting a mounting for the type wheels and within

which the type wheel advancing device is substantially enclosed and thereby protected from dust and damage from other causes.

Further objects of my invention are to provide a simple and effective arrangement for properly and positively aligning the characters or numbers of the type wheels before each imprinting operation; to move the usual ink pad frame towards and away from the printing or type wheels in a novel manner; and to provide a simple and effective construction for locking the usual plunger box carrying the type wheels and their actuating means, in a depressed position to thereby hold the ink pad frame in such a position as to render the ink pad readily accessible for re-inking, removal and replacement.

In general my invention resides in a numbering machine which is not only less complicated and less expensive to manufacture than previous machines of a similar character, but in which many of the principal operating parts are more rugged and subjected to less wear whereby the machine will have greater stability in operation and a longer life.

Other objects and features of my invention will be hereinafter specifically described and claimed.

While my invention may be expressed in various mechanical forms, for purposes of illustration the preferred form as applied to a "three-movement" numbering machine of the type disclosed in my said application Serial No. 174,298, is shown in the drawings accompanying and forming part of this specification, in which drawings,—

Figure 1 is a view in side elevation, partly in section and partly broken away, of a numbering machine embodying my invention;

Fig. 2 is a view in front elevation, partly broken away, of the machine shown in Fig. 1;

Fig. 3 is a sectional view taken on line 3—3 of Fig. 2;

Fig. 4 is an enlarged detailed view in side or end elevation, partly in section, and looking from the left with reference to Fig. 5, showing one of the numbering or type wheels with its retaining pawl, and the type wheel actuating or advancing means including the

oscillatory barrel which constitutes the support for the type wheels and the working pawl, the parts being shown in the position they occupy at the end of the return stroke and at the beginning of the working stroke of the working pawl;

Fig. 5 is a view in rear elevation of the structure shown in Fig. 4, showing however two of the type wheels, the retaining pawls 10 for the type wheels being omitted;

Fig. 6 is an enlarged detailed view in side or end elevation, partly in section, showing the oscillatory barrel, the working pawl, the control mechanism for the working pawl 15 when in the duplicate setting, and the retaining pawls and lift lever associated with the control mechanism, the parts being shown in the position they occupy at the beginning of the return and the end of the working stroke 20 of the working pawl; and

Fig. 7 is a view in elevation, looking from the right in Fig. 6.

Referring to the drawings reference character 1 represents the usual inverted U-shaped 25 main frame of the machine, which frame has the numbering wheel head and the principal operating mechanism of the machine mounted between its sides or legs. A plate 2 is suitably secured, as by screws 2', to the 30 lower ends of the legs of frame 1 and has an opening 3 through which the type of the numbering or type wheels project in imprinting or stamping the numbers. Reference character 4 represents a vertical stem or rod 35 secured at its lower end to the numbering wheel head and extending upwardly through an opening provided in the top of frame 1 at the center thereof, and also loosely through a cylindrical sleeve 5 having an enlarged or 40 flanged lower annular end 5'. The sleeve 5 is fixed to the top of frame 1 as by having its lower end 5' brazed thereto. The stem 4 has a handle or knob 6 secured to its upper end as by being threaded thereon, and said 45 knob is provided with a cylindrical axial recess 6' within which the upper end of sleeve 5 extends when the stem and numbering wheel head are in their uppermost or raised positions. A washer 7 is mounted on the 50 shouldered upper end of the stem 4 at a point adjacent the inner end or bottom of the recess 6', and a helical spring 8 disposed about the stem and within the sleeve 5 and handle 6 coacts with washer 7 and the lower end 5' 55 of the sleeve normally to yieldingly hold the stem and thereby the numbering wheel head in raised position, as shown in Figs. 1 and 2. Some distance above the numbering wheel head, the stem 4 is provided with a notch 9 having a lower horizontal wall and an upper 60 inclined wall, and mounted on the top of frame 1 is a slide 10 adapted to coact with said notch to lock the stem together with the numbering wheel head and the parts carried 65 thereby in partially depressed position. The

slide 10 is in the form of a flat substantially rectangular piece of sheet metal having a central square opening 11 through which the stem 4 normally loosely extends, the sides of such opening being slightly longer than the diameter of the stem. The slide 10 is supported from the top of frame 1 just beneath the same, by means of two upstanding T-shaped end projections 12 formed on the slide and respectively extending through T-shaped openings 13 in said top. It will be apparent that when stem 4 and the numbering head are depressed to a position in which the notch 9 is adjacent the slide 10, they may be effectively locked in such depressed position merely by moving the slide 10 to the left, referring to Figs. 2 and 3, so as to engage a right-hand edge portion of the opening 11 in the slide with said notch. The ink pad carrier will then have been removed from the path of the numbering or type wheels, as will be hereinafter described, and by means of the locking device just described, will be rigidly held in such a position as to render the ink pad readily accessible for re-inking, removal and replacement. To now release the stem 4 and numbering wheel head, it is merely necessary to depress the same from the locked position thereof by applying pressure to the handle 6 whereupon the upper inclined wall of notch 9 will engage the adjacent wall of opening 11 and coact therewith to move the slide 10 to the right, referring to Figs. 2 and 3, to non-locking position, and if the pressure is then removed from handle 6, the spring 8 will at once act to return the stem 4 and numbering wheel head to their uppermost or raised position. The heads of the T-shaped end projections 12 of slide 10 are of such size that they will pass through the extreme right-hand end or head portions of the T-shaped openings 13 in the top of frame 1, but only through such portions of said openings, which construction renders it possible to easily apply the slide to the frame in assembling the machine.

The numbering wheel head or plunger box, indicated at 14, is in the form of a yoke or inverted U, and a barrel 15 having an axial cylindrical opening 15' extending therethrough, is mounted in a horizontal position between the legs or side members of said head or box for oscillatory movement, by means of the short cylindrical slightly reduced sections 16 fixed to the ends of the barrel and journaled in suitable openings provided in said legs or side members. The sections 16, which may be considered as parts of the barrel 15, also serve to close the axial opening 15' at its ends, and are provided with central reduced cylindrical projections 16' on their inner sides which extend into and fit closely within the end portions of said opening and thereby act to center the sections 16 when the latter are applied to the

barrel. These cylindrical end sections of the barrel are also provided centrally thereon with reduced cylindrical portions or pins 17 which extend outwardly beyond the sides of the head 14 and into vertical guideways 18 formed in the legs of the main frame 1, the ends of said pins being closely adjacent the bottoms of the respective guideways. Anti-friction rollers 19 loosely mounted on the 5 ends of pins 17 and disposed and fitting fairly closely in the guideways or slots 18, coact with the latter to guide the head 14 in its reciprocatory movements in the main frame. The pins 17 respectively extend through 10 actuating arms 20 which are disposed between the end sections 16 of the barrel 15 and the rollers 19 and which are secured to said end sections in the same angular relation thereto, as by screws 21, these screws also 15 serving to rigidly secure the end sections 16 to the main body portion of the barrel 15. The arms 20 are provided at their outer ends with slots 22 which are respectively engaged by inwardly extending portions of members 23 rigidly secured, as by means of screws 24, 20 to the legs or side members of the stationary main frame 1, and coact with said members to oscillate the barrel 15 upon reciprocatory movement of the head 14 in the frame 1.

25 The type or numbering wheels 25, of which there are six in the machine illustrated, are annular in form and are arranged side by side within the yoke or head 14 and rotatably mounted on the barrel 15, these wheels being respectively the usual units, tens, hundreds, thousands, tens of thousands and hundreds of thousands wheels. Other suitable 30 series of wheels may be employed and the number of wheels used may, of course, also be varied as desired. The wheels 25 are disposed closely adjacent each other and a spacing ring 26 is loosely mounted on the barrel 15 between the numbering wheel of the highest order and the adjacent side member of the head 14. Reference characters 27 and 28 represent annular members comprising parts 35 of my improved mechanism for controlling the operation of the working or stepped pawl, for various settings of the machine, said members being respectively referred to herein as the "control ratchet" and the "ratchet governor" or "control ratchet governor". The members 27 and 28 are rotatably mounted on the barrel 15, in the order named, between the units wheel 25 and the adjacent leg or side member of the head or yoke 14, and are maintained in spaced relation by the hub or integral sleeve 29 with 40 which the control ratchet 27 is provided. The members 27 and 28 are resiliently connected by means of a spiral flat spring 30 having its inner end secured to the hub 29 of member 27 and its outer end secured to a projection 31 which is provided on the member 28 at the outer edge of the latter and

which extends laterally therefrom so as to lie in the path of a projection or tooth 32 formed on the outer edge of the control ratchet 27. The spring 30 constantly tends to maintain the control ratchet 27 in such a 45 position relative to the control ratchet governor 28 that the tooth or stop 32 on the former will engage the lateral projection 31 of the latter, and the arrangement is such that rotary movement of the control ratchet with respect to the ratchet governor to the right, referring to Fig. 6, that is, in such direction that the tooth 32 is moved away from the projection or stop 31 on the ratchet governor, will wind up or increase the tension of the spring.

50 Each of the numbering wheels 25 is provided on one side with an outside ratchet 34, which may be either formed integrally therewith or separately therefrom and affixed thereto. Because of manufacturing difficulties the ratchets 34 are preferably formed separately from the wheels 25, and are fixed to the latter concentrically therewith, as by being riveted thereto. Retaining pawls 35 55 which are pivotally mounted on a transversely extending rod 36 secured at its ends in the opposite sides of the yoke 14, respectively coact with the ratchets 34 to prevent backward movement of the wheels 25 in the return movements of the working pawl, which are effected upon the down-strokes of the head 14 in the frame 1, and to permit the actuation or advancement of the wheels upon the forward or working strokes of the working pawl, which are effected in the up-strokes of the head 14 in frame 1. Leaf springs 37 secured at one end, as by screws 38, to the under side of the top of the yoke or head 14, bear at their other end on the pawls 35 and 60 constantly tend to hold the same in engagement with ratchets 34. Each of the numbering wheels 25, as is customary, is provided with nine equi-spaced shallow notches 39 and a deep long notch 40 in the inner annular edge thereof, these notches having the usual disposition, i. e., there is one shallow notch 39 for each of nine of the ten numbers on the wheel and the deep long notch 40 is employed for the tenth number and for the 65 purpose of "carrying" to the wheel which is of the next order. Where my invention is adapted to a three-movement machine, as shown herein, the control ratchet 27 is provided on its inner periphery with but two notches, viz a deep long notch 41 and a shallow long notch 42 running into the deep notch 41. It will thus be apparent that the 70 said inner periphery of number 27 is for the greater part of its length, smooth or unnotched. The inner periphery of the ratchet governor 28, however, has no notches at all, being smooth for its entire length. The notch 42 of the control ratchet 27 is of uniform depth for the greater portion of its 75

80

length, the bottom of such portion being formed on an arc concentric with the axis of the said ratchet, but for a purpose which will hereinafter be explained, such notch is provided with a short section 43 adjacent the deep notch 41 which is of gradually increasing depth in a direction towards the latter notch, the bottom of said section 43 thus being on a slight incline.

5 The main body portion of the barrel 15 is provided with a longitudinally extending slot or cut-away portion 45 extending inwardly from the surface of the barrel and intercepting the axial opening 15', and also, at 10 its ends, with arcuate slots or recesses 46 which intercept the axial opening 15' and the slot 45. The working pawl comprises a pawl bar 47 having integral crank arms 48 at its ends, a series of integral stepped pawls 49 corresponding in number with and adapted 15 to coact respectively with the numbering wheels 25, and a single integral pawl or tooth 50 located between the pawl 49 which is adapted to coact with the units wheel and the crank arm 48 at the adjacent end of the 20 working pawl. The pawl or tooth 50 is slightly longer than the adjacent longest pawl of the series of stepped pawls 49 and is adapted to coact with the control ratchet 25 25 27 at the inner periphery of the latter. The working pawl is mounted on the barrel 15 with its crank arms 48 disposed in the arcuate recesses 46, and is pivotally supported in this position by means of pins 51 fixed in the 30 opposite end portions of the barrel and having portions which extend into the recesses 46 and loosely engage aligned openings in said crank arms. The pawl bar 47 of the 35 working pawl as thus mounted, is adapted for inward and outward movements with respect to the axis of barrel 15, about the pins 51, and, with the machine assembled, is received in the axial opening 15' and the longitudinal slot 45 of the barrel. The said opening 15' and slot 45 are of such size and shape 40 as to accommodate the pawl bar 47 in all the various positions it assumes in the operation of the machine and thereby provide for proper coaction of the pawls 49 and 50 with the type wheels 25 and control ratchet 27. Adjacent one end the barrel 15 is provided with 45 an additional arcuate recess or slot 52 through which one of the pins 51 extends, and disposed in this slot and coiled about the 50 said pin is a spring 53. The spring 53, which is under tension, bears at one end against the barrel 15 and at the other end against the pawl bar 47, and therefore constantly tends to force the pawl bar outwardly about the 55 pivot pins 51 and into coacting engagement with the notched inner peripheries of the annular numbering wheels 25 and the control ratchet 27.

60 When the yoke or head 14 is reciprocated 65 in the main frame 1, the barrel 15 and thereby

the pawl bar 47 are oscillated to advance the numbering wheels by the usual step-by-step movements; it being understood, of course, that when the machine is set for "duplicate" the pawl bar will be held from coacting with 70 and advancing the numbering wheels in every other reciprocation of the head 14, while when the machine is set for "repeat" the pawl bar will be continuously held from coacting with and advancing the numbering wheels. As 75 indicated above, such oscillatory movement is directly imparted to the barrel 15 and thereby to the pawl bar 47 upon the up and down reciprocatory movements of the head 14, by reason of the engagement of the members 23 80 carried by the stationary main frame 1, with the slots 22 of the actuating arms 20 carried by the barrel. The arrangement is such that the return movements or strokes of the pawl bar are effected upon the printing or down 85 strokes of the head 14, and the advancing or working strokes of the pawl bar are effected upon the return or up strokes of said head. However, in a machine of the construction shown and described herein, the pawl bar 47 90 is held by reason of the engagement of its long tooth or pawl 50 with the bottom of the shallow working notch 42 in the control ratchet 27, from coaction with the type wheels 25 at all times except when the control ratchet 95 is in a position in which the deep clearance notch 41 thereof is directly opposite the pawl bar so as to be adapted to accommodate the latter. When the control ratchet is thus positioned, the notch 41 therein permits the working pawl to engage the type wheels, and the said pawl will then, upon each of its working strokes, actuate or advance said wheels. Such working strokes of the stepped pawl will be referred to herein as actuating strokes. 100

The machine is provided, as is customary, with an ink pad frame 55 adapted to carry a pad (not shown) for inking the type or numbers of the wheels 25. The ink pad frame 55 is pivotally supported from the stationary main frame 1 by pins 56 (only one of which is shown) which extend through arms 57 provided at the opposite ends of the ink pad frame and into the adjacent side members or legs of the main frame. Movements of the 105 ink pad frame 55 towards and away from the type wheels 25 about the pivot pins 56 are effected by the barrel 15 in the up and down and oscillatory movements of the latter, upon reciprocation of the head 14, through links 110 58 which are pivotally connected at their opposite ends respectively to the frame 55 and the barrel 15 by means of pins 59 and 60. The arrangement is such that as the numbering head 14 is reciprocated in frame 1, the 115 ink pad frame 55, upon the down or printing movement of the head 14, will be moved outwardly by the barrel 15 about the axis of pivot pins 56 to that position in which the same is most remote from the wheels 25; while upon 120 125 130

the up or return movement of the head, the said frame 55 will be moved inwardly by the barrel about the pins 56 so that upon the completion of such return movement a pad carried by such frame will be pressed firmly 5 against the type or numbers of the wheels 25 which are to perform the next printing.

The "settings" of the machine are determined by the index positions or settings given the control mechanism comprising the control ratchet 27 and the ratchet governor 28, such control mechanism governing the action of the working pawl and being adapted when in a setting other than the "repeat" setting to prevent actuation or advancement 10 of the numbering wheels by the working pawl until a predetermined number of actuations of the machine and of working strokes of the working pawl. In the machine described herein the operative settings have preferably been limited to three, namely: to "consecutive," "repeat" and "duplicate." The ratchet governor 28 is adapted to be moved about the axis of barrel 15 to and firmly but yieldingly or releasably locked in any one of three angular 15 positions corresponding respectively to the three settings of the machine. A desired index setting of the control mechanism and thereby of the machine is effected merely by moving the ratchet governor to the angular 20 position thereof corresponding to such setting. The ratchet governor is provided with an elongated extension 62, serving as an index lever, whereby the said governor may be 25 positively and directly moved from any of said angular positions thereof to any other such position to thereby effect a change in the setting of the machine. A front plate 63 is secured as by screws 64, to the head 14 and is 30 provided with a vertical slot 65 through which the indexing lever 62 extends, and a change in the setting of the machine is effected simply by moving said lever, which constitutes the only indexing mechanism employed in the machine herein described, up 35 or down in said slot to a position therein corresponding to the setting desired; the proper positions of lever 62 in slot 65 for the "repeat," "duplicate" and "consecutive" settings being respectively indicated by the characters 40 "R", "D" and "C" applied to the front plate 63 adjacent said slot. The ratchet governor 45 28 has three angular notches 66, 67 and 68 in its outer edge or periphery which respectively correspond in their location with the "repeat", "duplicate" and "consecutive" positions or settings of the governor, and a pawl 69 mounted on the rod 36 and constantly pressed towards said ratchet governor by a 50 spring arm 37', is provided with a rounded end arranged to engage that one of said notches corresponding to any index setting or position of the governor to thereby yieldingly but releasably lock the latter in such 55 position. In addition to the laterally extend-

ing projection or lug 31, the ratchet governor 28 is provided at its outer edge with two similar lugs 70 and 71, these three lugs being substantially equi-spaced and extending over or across the control ratchet 27 to engage the outer face of the adjacent units wheel 25 for the purpose of maintaining the ratchet governor properly spaced from such wheel and prevent the same from interfering with the proper operation of the control ratchet and the spring 30.

The periphery of the control ratchet 27 is provided, in addition to the tooth or step 32, with a notch 72 one wall 73 of which extends in a substantially radial direction and provides an abrupt shoulder, and the other wall or side 74 of which is in the form of a long cam surface inclining outwardly from the wall 73 and finally merging in the main surface portion of the periphery of the ratchet. A retaining pawl 75 for the control ratchet 27 is pivotally mounted at one end on the rod 36, and a spring arm 37' secured to the head 14 bears against said pawl and constantly tends to force the same towards the control ratchet. This retaining pawl 75 is provided intermediate its ends with a tooth 76 adapted to coact with the notch 72 of the control ratchet, with a cam 77 between the tooth 76 and the pivot end thereof with which cam the spacer or lug 71 of the ratchet governor is adapted to coact, and with a notch 78 adjacent its free end and with which the spacer or lug 31 of the ratchet governor is adapted to coact. A lever 79, which I shall refer to as a lift lever, is pivotally mounted at its lower end on a stud or pin 80 secured in and projecting from the adjacent leg or side member of the head 14, and a spring 81 coiled about said pin and having one end engaging a small opening 82 in said leg and the other end bearing against said lever constantly tends to force the latter towards the control ratchet 27 and the lug 31 of the ratchet governor 28. The lift lever 79 has, intermediate the ends thereof, a cam portion 83 with which the tooth or projection 32 of the control ratchet and the lug 31 of the ratchet governor are adapted to coact; and at its upper end the said lift lever has an angular or laterally extending portion 84 adapted to coact with the retaining pawl 75.

The spring arms 37, 37' and 37" which respectively bear on the pawls 35, 69 and 75, are preferably formed from a single resilient sheet metal member and extend from a portion of such member secured to the top of the frame or head 14 by screws 38 (only one of which is shown). For the purpose of better protecting and shielding its operating parts as well as to give a better appearance to the machine, a rear cover plate 85 is secured, as by screws 86, to the main frame 1.

The adjustment of the machine to and the operation thereof in each of the various set-

tings for which it is adapted will now be described:

Repeat setting

To adjust the machine to the "repeat" setting it is merely necessary to move the arm or indexing lever 62 to its uppermost position in the slot 65 of the front plate 63 opposite the indication "R" on the latter. Such movement of the indexing lever 62 moves the ratchet governor 28 about its axis to a position in which the notch 66 thereof is engaged by and coacts with the rounded end of the locking pawl 69 to thereby yieldingly lock the control mechanism in the "repeat" setting thereof. In the movement of the ratchet governor 28 to this position the lug 31 thereof engages the wall of the notch 78 in the retaining pawl 75 and raises the latter to the position shown in full lines in Fig. 1, in which its tooth 76 is wholly out of engagement with the periphery of the control ratchet 27 and its free end is above and clears the upper angular end portion 84 of the lift lever 79. Thereupon the lift lever is moved by spring 81 into engagement with the periphery of control ratchet 27 and the spring 30 exerts an action tending to move the control ratchet in anti-clockwise direction, referring to Fig. 6, to bring the stop or tooth 32 thereof into engagement with the lug 31 of the ratchet governor in the new position of the latter. Such movement of the control ratchet, however, is prevented or limited by reason of the engagement of the long tooth 50 of the working pawl 47 with the shoulder formed at the end of the long portion of the shallow notch 42 in the ratchet which is of uniform depth, and consequently the setting of the ratchet governor, as described, results in winding up or increasing the tension of the spring 30. If the machine is now repeatedly actuated the control ratchet is merely oscillated or moved back and forth, about its axis, with the working pawl 47 and the barrel 15, and the tooth 50 of said pawl is constantly maintained in engagement with the shoulder at the end of the notch 42 in the control ratchet with the result that none of the numbering wheels 25 is advanced and the same number is therefore printed over and over. In this connection it is to be noted that whenever the longest tooth or pawl 50 of the working pawl engages the long portion of the notch 42 in the control ratchet, the working pawl is thereby held in a position inwardly of that in which any of the other teeth or pawls 49 thereof would engage the inner periphery of any wheel 25. With the machine in this "repeat" setting none of the working strokes of the working pawl will be an actuating stroke. In each down stroke of the head 14 and the accompanying return stroke of the working pawl, the control ratchet, under the action of the tensioned spring 30, turns in a direction to move the tooth or stop

32 thereof towards the lug 31 of the ratchet governor 28, and the shoulder at the end of the shallow notch 42 therein is maintained in engagement with the long tooth 50 of the working pawl; while in each up-stroke of head 14 and the accompanying working stroke of the working pawl, the control ratchet is turned in the opposite direction against the action of spring 30, and thus restores tension in the latter, by reason of the engagement of the tooth 50 of the working pawl with the shoulder of the end of the notch 42 in the ratchet.

Duplicate setting

To now adjust the machine to its "duplicate" setting the indexing lever 62 is moved downwardly from the "repeat" position thereof to a position substantially midway between the ends of slot 65 and opposite the indication "D" on the front plate 63. Such movement of lever 62 turns the ratchet governor 28 to a position in which the notch 67 in the periphery of the latter is engaged by the rounded end of the spring 90 pressed pawl 69 and thus results in yieldingly locking the control mechanism in its new or "duplicate" setting. The lug 31 of the governor 28 is now in the position shown in Fig. 6 and accordingly does not act to prevent the retaining pawl 75 from moving, under the action of spring arm 37², into engagement with the periphery of the control ratchet 27. The arrangement is such that in this adjustment of the machine to its "duplicate" setting, the lift lever 79 is moved by its spring 81 into engagement with the edge of the ratchet at a point between the tooth or stop 32 and the notch 72, before the pawl 75 is disengaged by the lug 31 of the governor and thereby allowed to move inwardly a sufficient distance to engage the tooth 76 thereof with said ratchet. The result is that the upper angular end portion 84 of the lift lever is positioned beneath the end of the retaining pawl 75 so as to prevent the latter from moving inwardly to a position in which its tooth 76 is adapted to coact with the notch 72, and said end portion remains thus positioned until the lift lever 79 is moved outwardly by the tooth 32 of the control ratchet during the actuation of the machine in the new setting thereof, as will presently be described. The adjustment of the machine to the "duplicate" setting, as well as to any other setting, is preferably effected when the numbering head 14 is in its normal raised position, shown in Figs. 1 and 2. The working pawl is now at the end of a working stroke with the long tooth or pawl 50 thereof in engagement with the shoulder at the end of the long shallow notch 42 of the control ratchet 27, as shown in Fig. 6. Upon now actuating the machine the cycle of operations is as follows: On the first down-stroke of the

head 14 the number set up on the wheels, is, of course, printed, a return stroke is imparted to the working pawl 47, and the control ratchet 27, under the action of spring 30, merely follows the movement of the working pawl, with the said shoulder at the end of the notch 42 maintained in engagement with the long tooth 50 of said pawl, and turns about its axis in a direction to bring the tooth or stop 32 thereof against the lug 31 of the ratchet governor 28. In the last part of this turning movement of the control ratchet the peripheral portion thereof having the notch 72 is carried to the left, referring to Fig. 6, past the tooth 76 of the retaining pawl 75, and the tooth 32 of said ratchet then engages the cam portion 83 of lift lever 79 and moves the latter outwardly against the action of spring 81 and about the pin 80 until the angular end portion 84 of the lever clears the free end of said retaining pawl, and thereupon the retaining pawl 75, under the action of spring arm 37², moves inwardly to a position in which the tooth 76 thereof engages the periphery of the control ratchet at a point between the notch 72 and the tooth 32. On the next or first up-stroke of head 14, a working stroke is imparted to the working pawl 47, but such working stroke is not an actuating stroke and none of the numbering wheels is advanced therein because of the fact that the long tooth 50 of the working pawl remains in engagement with the long portion of the notch 42 of the ratchet 27 throughout such stroke and all the remaining teeth or pawls 49 are thereby prevented from engaging the inner peripheries of the wheels 25 with which they are respectively adapted to coact. In this working stroke of the pawl 47, however, the tooth 50 thereof engages the shoulder at the end of notch 42 in the ratchet and moves the latter against the action of spring 30, thus restoring tension in such spring, to the position shown in Fig. 6, and the pawl 75 thereupon is moved inwardly still further by spring arm 37² and the tooth 76 thereof is engaged with the notch 72 of the ratchet. On the next or second down-stroke of head 14 the number set up on the wheels 25 is printed a second time and a return stroke is, of course, imparted to the working pawl 47. In this return stroke of the working pawl, however, the ratchet 27 moves with said pawl, under the action of spring 30, only a short distance during the first part of such stroke, further movement of the ratchet being prevented by the engagement of the wall 73 of the notch 72 with the tooth 76 of the retaining pawl 75; during the last part of such return stroke the ratchet 27 is held stationary by the tooth 76, and the long tooth 50 of the working pawl rides over the bottom of the main portion of the shallow notch 42 in the ratchet 27,

then over the short inclined portion 43 thereof and finally enters the deep notch 41. It is thus apparent that the working pawl is now adapted to coact with one or more of the numbering wheels 25 upon the ensuing working stroke thereof, or, in other words, that such working stroke will be an actuating stroke. On the next or second up-stroke of head 14 such an actuating stroke is imparted to the working pawl 47 which, of course, results in the actuation or advancement of one or more of the numbering wheels 25, depending on the number then set upon the wheels, such actuation of each wheel thus advanced, as will be understood, being effected by the engagement of one of the teeth 49 of the working pawl with one of the notches 39 and 40 of the wheel. In this actuating stroke of the working pawl (and this is true of all actuating strokes of said pawl) the long tooth 50 thereof also engages that portion of the wall of the deep notch 41 in ratchet 27 which is adjacent the long shallow notch 42, and turns said ratchet through such an angle to the right, referring to Fig. 6, with the numbering wheel or wheels being advanced and against the action of spring 30, that the cam surface 74 forming one wall of the notch 72 in the ratchet acts on the tooth 76 of pawl 75 and thereby raises the latter to a position in which the end thereof is clear of the upper angular end portion 84 of the lift lever 79. When the pawl 75 is thus raised the lift lever 79 is moved by spring 81 to a position in which its cam portion 83 engages the periphery of ratchet 27 at a point therein between the notch 72 and the tooth 32 and in which its angular end portion 84 is disposed beneath the free end of said pawl and is adapted to maintain the latter in inoperative relation to the ratchet. The first cycle of operations has now been completed and no further change in position of any of the parts is effected, while the "duplicate" setting is maintained, until the head 14 is given the first down-stroke in the next succeeding or second cycle of operations of the machine.

The said second cycle and every other succeeding cycle of operations, in this "duplicate" setting of the machine differs from the first cycle of operations, just described, only in the operations which are effected upon the first down-stroke of the head 14 in such a succeeding cycle, and I shall now proceed to describe in proper sequence the operations so effected. It is to be borne in mind that the working pawl 47 has just completed a working stroke, which was also an actuating stroke, in which it advanced one or more of the numbering wheels 25 and is now at the beginning of a return stroke with each tooth 49 thereof which effected the advancement of any such wheel still engaging one of the notches in the inner periphery of the wheel,

and with the long tooth 50 thereof engaging the wall of the deep notch 41 in the control ratchet 27 at a point adjacent the short inclined section 43 of the shallow notch 42, 5 thereby holding said ratchet in an angular position to the right of that shown in Fig. 6 and in which the high portion of the long cam-shaped wall 74 of notch 72 therein engages the tooth 76 of the retaining pawl 75 10 and holds the latter raised with its free end above and clear of the upper end of the lift lever 79. The lift lever is now, of course, in a position to the left of that shown in Fig. 6 with the cam portion 83 thereof bearing 15 against the periphery of ratchet 27 at a point between the tooth 32 and the notch 72. Also, as is customary, the construction is such that each of the numbering wheels which has just been actuated was advanced to and is now 20 in an angular position slightly beyond that in which the retaining pawl 35 for such wheel would engage one of the teeth of the ratchet 34 carried by the wheel. The down-stroke now being given to the head 14 by the depression of knob 6, the barrel 15 is, of course, 25 turned to impart a return-stroke to the working pawl 47. In the very first part of this return stroke each wheel 25 actuated in the previous working stroke of the pawl 47, is, 30 because of the engagement of a tooth 49 of said pawl with a notch on the inner periphery of the wheel, turned slightly in the opposite direction to that in which it was just advanced so as to bring such wheel into 35 proper alignment with the remaining wheels 25 and the proper tooth of the ratchet 34 thereof into firm engagement with the retaining pawl 35 therefor. The pressure exerted by this spring-pressed retaining pawl 40 on the inclined rear face of an adjacent tooth of the said ratchet 34 also tends to turn the respective wheel 25 in the same direction and therefore assists in bringing such wheel into alignment, as will be clear from 45 Figs. 1 and 4.

Furthermore, the barrel 15 in the turning movement thereof which imparts the return stroke to the working pawl, also acts, by reason of its frictional engagement with the 50 inside of said wheels, to align each of the wheels 25 last advanced as well as any other wheels which may be out of alignment, and thereafter frictionally acts to maintain all the wheels in proper alignment until the 55 down-stroke of the head 14 has been completed and the number then set up on the wheels has been printed. The alignment of the wheels 25 is thus simply effected and there is no occasion to provide any means other than 60 the teeth 49 of pawl 47, to coact with the operating notches on the inside periphery of said wheels. Accordingly the said operating notches are made unusually wide with large contact surfaces which will result in longer 65 life and improved action. Immediately

after a wheel 25 last advanced has thus been brought into alignment, the pawl 47, through the coaction of one side or wall of an operating notch of such wheel with a pawl 49 as the return stroke of said pawl progresses, is 70 moved inwardly about its pivot pins 51 to a position in which the said tooth 49 thereof is almost if not quite clear of the said operating notch, and in which its long tooth 50 is withdrawn from the deep notch 41 of ratchet 75 27 and bears on the adjacent short inclined bottom section 43 of the long shallow notch 42. Thereupon the spring 30 at once acts to turn the ratchet 27 very rapidly to the left, referring to Fig. 6, until the same is brought to a 80 position where the shoulder at the end of the shallow notch 42 engages the tooth 50 of the pawl 47. The retaining pawl 75, however, is now prevented from engaging the ratchet 27 by the upper angular end portion 85 84 of the lift lever 79 as the latter still engages the outer periphery of said ratchet at a point between tooth 32 and notch 72. In the said rapid movement of ratchet 27 the short inclined bottom section 43 of its notch 90 42 acts on tooth 50 of the working pawl and moves the latter inwardly still further about the pins 51 to a position in which all of the teeth 49 thereof are entirely free from engagement with the inner peripheries of the 95 wheels 25. The head 14 has now moved through but a small part of its down-stroke and the pawl 47 but a small part of its return stroke. As the down-stroke of head 14 is now continued, the pawl 47 continues to 100 move in its return stroke about the axis of barrel 15 and the ratchet 27, under the action of spring 30, follows such movement of the pawl with the shoulder at the end of its notch 42 maintained in engagement with the 105 pawl tooth 50. Shortly before the down stroke of the head 14 is completed the tooth 32 of ratchet 27 engages the cam section 83 of lift lever 79 and moves the latter about the pin 80 against the action of spring 81 to a 110 position in which the upper end portion 84 thereof is clear of the free end of the retaining pawl 75, and the latter thereupon moves downwardly to a position in which its tooth 76 engages the periphery of the ratchet at a 115 point therein between the notch 72 and the tooth 32. It will therefore be apparent that in the construction described the ratchet 27 acts automatically both to disengage itself from its retaining pawl 75 and to effect the 120 re-engagement of said pawl with itself—such disengagement being effected upon a forward or advance movement of the ratchet and such re-engagement being effected upon a reverse movement of the ratchet under the 125 action of spring 30. The number now set up on the wheels 25 is, of course, printed upon the completion of the down-stroke of head 14 and the return stroke of pawl 47.

In adjusting the machine to its "duplicate" 130

setting from the "consecutive" setting thereof, the indexing lever 62 is merely moved upwardly in slot 65 of the front plate 63 from the position indicated by the character "C" to that indicated by character "D". The rounded end of pawl 69 now engages the notch 67 in the ratchet governor 28 and yieldingly locks the control mechanism in proper position for the said duplicate setting. As the previous working stroke of pawl 47 was an actuating stroke in which one or more of the numbering wheels 25 was advanced, the pawl 47, ratchet 27, retaining pawl 75 and lift lever 79 are now in exactly the same positions they occupied at the beginning of the first down-stroke of head 14 in the second cycle of operations of the machine when the latter was changed to "duplicate" setting from the "repeat" setting thereof as described above. Accordingly when the setting of the machine is changed to "duplicate" from "consecutive" all the cycles of operations of the machine, including the first and every succeeding cycle, are similar in all respects and are each identical with any cycle of operations, except the first, of the machine in the case where the latter has been changed from the "repeat" setting to the "duplicate" setting.

39 *Consecutive setting*

In adjusting the machine to its "consecutive" setting it is merely necessary to move the index lever 62 downwardly in slot 65 of the front plate 63, from either the "repeat" or "duplicate" positions thereof, to the position indicated by character "C". Such movement of lever 62 turns the ratchet governor 28 to a position in which the rounded end of the pawl 69 engages the notch 68 in the governor and thus yieldingly locks the control mechanism in proper position for the "consecutive" setting of the machine. In this position of the governor 28 the lugs 31 and 71 thereof respectively engage the cam portion 83 of lift lever 79 and the cam 77 of retaining pawl 75 and thereby hold said lever and pawl out of cooperative relation with the control ratchet 27 in the positions shown in Fig. 1. The lug or stop 31 of the governor 28 is also now so positioned that the control ratchet 27 can turn in a reverse direction, under the action of spring 30, when following the movement of the working pawl 47 in any return stroke thereof, only a short distance before the tooth 32 engages said stop or lug and such movement of the ratchet is thereby arrested. Accordingly in this "consecutive" setting of the machine, upon each down-stroke of the head 14 to effect a printing of the number set up on the wheels 25, the ratchet 27 is arrested in such a position that the tooth 50 of pawl 47 at or near the end of the accompanying return stroke of the latter, enters the deep or "clearance" notch 41 of the ratchet with

the result that at least one of the teeth 49 of said pawl is then adapted to engage an operating notch on the inner periphery of one of the wheels 25 upon the working stroke of pawl 47 accompanying the following up-stroke of the said head 14. It will therefore be apparent that each working stroke of the machine will now be an actuating stroke effecting an advancement of one or more of the wheels 25 and that the machine upon successive actuations thereof, will print consecutively.

70 The machine described is of simple and rugged construction and the operation thereof is accompanied by a minimum of wear. Most of the principal operating parts are effectively protected against injury. In this connection it is to be noted that the working pawl is substantially entirely enclosed by the barrel and the numbering wheels and other elements carried by said barrel; whereby it is practically impossible for dust or dirt to gain access to said pawl and interfere with its proper operation.

75 Some of the features of my invention are not limited in their application to numbering machines of the character described herein, but are equally applicable to various other types of numbering machines. It is also to be understood that the specific construction shown and described herein is subject to numerous modifications and changes in the size, shape and arrangement of parts without departure from the spirit of my invention or the scope of the appended claims.

80 Having now described my invention, what I claim as new and desire to protect by Letters Patent is as follows:

85 1. In a numbering machine, a series of numbering wheels, pawl means adapted to impart to said wheels only the advance movements thereof which effect the changes in the numbers set up by the wheels, and means for actuating said pawl means comprising an oscillatory barrel on which said wheels are mounted.

90 105 2. In a numbering machine, a frame, a head mounted on said frame for reciprocatory movement, a barrel mounted on said head for oscillatory movement, a series of numbering wheels mounted on said barrel, means operable by said barrel upon oscillatory movement thereof for imparting to said wheels only the advance movements thereof which effect the changes in the numbers set up by the wheels, and means whereby reciprocatory movement of said head effects oscillatory movement of said barrel.

110 115 120 125 3. In a numbering machine, a frame, a head mounted on said frame for reciprocatory movement, a barrel mounted on said head for oscillatory movement, said barrel having extensions cooperating with said frame to guide said head in such reciprocatory movement thereof, a series of numbering wheels mounted

on said barrel, means also mounted on the barrel and operable by the latter in its oscillatory movement for imparting to said wheels only the advance movements thereof which effect changes in the numbers set up by the wheels, and means whereby reciprocatory movement of said head effects oscillatory movement of said barrel.

4. In a numbering machine, a frame, a head mounted on said frame for reciprocatory movement, a barrel mounted on said head for oscillatory movement, said frame having guideways and the barrel having end portions carrying antifriction rollers respectively disposed in said guideway and cooperating therewith to guide said head in such reciprocatory movement thereof, a series of numbering wheels mounted on said barrel, means movable by the barrel in its oscillatory movement for imparting to said wheels only the advance movements thereof which effect changes in the numbers set up by the wheels, and means whereby reciprocatory movement of said head effects oscillatory movement of said barrel.

5. In a numbering machine, a series of annular numbering wheels having notched inner peripheries, and means for actuating said wheels to effect changes in the numbers set up thereby comprising an oscillatory barrel on which the wheels are mounted and a pawl device mounted on said barrel and adapted to coact with the notches in said wheels.

6. In a numbering machine, a series of type wheels, means for actuating said wheels comprising an oscillatory barrel on which the wheels are mounted and a pawl device pivotally mounted on said barrel and adapted to coact with said wheels, and mechanism for controlling said pawl device comprising a control member mounted on the barrel and adapted to coact directly with such device.

7. In a numbering machine, a series of type wheels, means for actuating said wheels comprising an oscillatory barrel on which the wheels are mounted and a pawl device pivotally mounted on said barrel and adapted to coact with said wheels, and mechanism for controlling said pawl device comprising a control member mounted on the barrel and adapted to coact directly with such device, said control member being adapted to be set in a plurality of different initial positions and thereby effect a corresponding number of different settings of the machine.

8. In a numbering machine, a frame, a head mounted on said frame for reciprocatory movement, a barrel mounted on said head for oscillatory movement, a series of numbering wheels mounted on said barrel, and means actuatable by said barrel upon oscillatory movement thereof for imparting to said wheels only the advance movements thereof which effect changes in the numbers set up by the

wheels, said barrel and frame having engagement whereby such reciprocatory movement of said head effects oscillatory movement of the barrel.

9. In a numbering machine, a main frame, a head mounted on said frame for reciprocatory movement, a barrel mounted on said head for oscillatory movement, a series of type wheels mounted on said barrel, means for advancing said wheels upon oscillatory movement of the barrel, means whereby said reciprocatory movement of the head effects oscillatory movement of said barrel, an ink pad frame movably mounted on the main frame, and means for moving said ink pad frame towards and away from said wheels upon reciprocatory movement of the head in said main frame comprising a connection between the ink pad frame and the barrel.

10. In a numbering machine, a main frame, a head mounted on said frame for reciprocatory movement, a barrel mounted on said head for oscillatory movement, a series of type wheels mounted on said barrel, means for advancing said wheels upon oscillatory movement of the barrel, means whereby said reciprocatory movement of the head effects oscillatory movement of said barrel, an ink pad frame pivotally mounted on the main frame, and means for pivotally moving said ink pad frame towards and away from said wheels upon reciprocatory movement of the head in said main frame comprising a link pivoted at one end to the ink pad frame and at the other end to the barrel eccentrically of the latter.

11. In a numbering machine, a series of numbering wheels, means for imparting to said wheels only the advance movements thereof which effect changes in the numbers set up by the wheels comprising a barrel mounted for oscillatory and reciprocatory movements on which said wheels are mounted, a frame for an ink pad adapted to co-operate with said wheels, and means whereby said barrel upon and by reason of such oscillatory and reciprocatory movements thereof effects movement of said frame towards and away from said wheels.

12. In a numbering machine, a series of numbering wheels, and mechanism for imparting to said wheels only the advance movements thereof which effect changes in the numbers set up by the wheels comprising means which is also operable to align said wheels before each imprinting operation.

13. In a numbering machine, a series of numbering wheels, and mechanism adapted to impart to said wheels only the advance movements thereof which effect changes in the numbers set up by the wheels comprising means which also serves as a support or mounting for said wheels.

14. In a numbering machine, a series of numbering wheels, and mechanism adapted

to impart to said wheels only the advance movements thereof which effect changes in the numbers set up by the wheels comprising means operable to align the type wheels before each imprinting operation, said means also serving as a support for said wheels.

15. In a numbering machine, a head, a series of type wheels, a support for said wheels carried by said head, said head being movable to move said wheels to and from imprinting position, and a movably mounted ink pad frame, said support being movable with respect to said head and being operable in and by reason of its movement with respect to the head to move said ink pad frame away from and toward said type wheels as the type wheels are respectively moved to and from imprinting position.

16. In a numbering machine, an oscillatory barrel, a plurality of members including a series of numbering wheels mounted on said barrel, and means enclosed by said barrel and members and actuatable by the barrel in its oscillatory movement for imparting to said wheels only the advance movements thereof which effect changes in the numbers set up by the wheels.

17. In a numbering machine, an oscillatory barrel, a plurality of members including a series of wheels mounted on said barrel, and a pawl device adapted to actuate said wheels upon oscillation of said barrel, said pawl device being pivoted on said barrel and being wholly enclosed by the barrel and said members.

18. In a numbering machine, a reciprocating head, an oscillatory barrel comprising a core section having a longitudinal cut-away portion and end sections journaled in said head, a series of numbering wheels mounted on said core section, a pawl device mounted on said barrel for pivotal movement in said cut-away portion and adapted upon oscillation of said barrel to impart to said wheels only the advance movements thereof which effect changes in the numbers set up by the wheels, and means whereby reciprocating movement of said head effects oscillatory movement of said barrel.

19. In a numbering machine, a reciprocating head, a series of annular numbering wheels carried by said head and having notched inner peripheries and outside ratchets, means for advancing said wheels to effect changes in the numbers set up thereby upon reciprocation of said head comprising a pawl device with which the notches in the inner peripheries of the wheels are alone adapted to co-act, and retaining pawls carried by said head and respectively coacting with the outside ratchets of said wheels to prevent any appreciable backward movement of the wheels.

20. In a numbering machine, a reciprocating head, an oscillatory barrel mounted on

said head, a series of annular wheels mounted on said barrel and provided with outside ratchets, means whereby reciprocatory movement of said head effects oscillatory movement of said barrel, means adapted upon movement of said barrel in one direction to actuate said wheels and retaining pawls carried by said head and coacting respectively with the outside ratchets of said wheels, said barrel upon movement thereof in the other direction frictionally coacting with the inner peripheries of the wheels to effect alignment of the latter.

21. An annular control ratchet adapted for cooperation with the working pawl of a numbering machine, said ratchet having on its inner periphery a deep "carrying" notch and a long shallow notch running into said deep notch.

22. An annular control ratchet adapted for cooperation with the working pawl of a numbering machine, said ratchet having on its inner periphery a deep "carrying" notch and a long shallow notch, said shallow notch having a long portion of uniform depth and a portion which extends from said long portion and runs into said deep notch and which increases in depth toward the latter.

23. In a numbering machine adapted to operate in a plurality of settings, mechanism for controlling the operation of the machine in each setting thereof comprising a control ratchet and a ratchet governor mounted coaxially with the numbering wheels for turning movement, said ratchet and governor having a resilient connection, and said governor being adapted to be directly and manually adjusted from the exterior of the machine and thereby effect any desired setting of the machine.

24. In a numbering machine, a main frame, a head carrying the numbering wheels mounted for reciprocatory movement in said frame and having an actuating stem or rod, and means for holding said head in a depressed position in said frame comprising a notch in said rod and a slide mounted on said frame for movement thereon into and out of coacting relation with said notch, said frame having spaced slots and said slide having integral angular portions extending through said slots whereby the slide may be manually operated, the ends of said angular portions being enlarged and cooperating with the walls of said slots to hold the slide on said frame.

25. In a numbering machine adapted to operate in a plurality of settings, a reciprocating head carrying the numbering wheels and having a plate provided with a slot applied thereto, and mechanism for controlling the operation of the machine in each setting thereof comprising a control member and a governor for such member, said control member and governor being mounted for turn-

ing movement and having a resilient connection, and said governor having an arm extending through the slot in said plate and adapted to be moved to any position in such slot and thereby directly effect the adjustment of the machine to any operative setting thereof.

26. In a numbering machine adapted to operate in a plurality of settings including a "consecutive" setting and a "duplicate" setting, a series of numbering wheels, mechanism for controlling the operation of the machine in each setting thereof comprising a control member mounted for turning movement and having a deep "carrying" notch and a shallow notch communicating with said deep notch, an oscillatory work-pawl for actuating said wheels having a tooth coacting with said control member and always engaging in one of the said notches therein, the working pawl being held in inoperative relation to said wheels whenever the said tooth engages said shallow notch, and being in operative relation to the wheels when such tooth engages said deep notch, said control mechanism including means whereby when the machine is in its "consecutive" setting, said tooth will engage the deep notch of said control member in each actuation of the machine, and when the machine is in its "duplicate" setting, such tooth will engage said deep notch only in every other actuation of the machine.

27. In a numbering machine adapted to operate in a "repeat" setting, a "consecutive" setting and a "duplicate" setting, a series of numbering wheels, mechanism for controlling the operation of the machine in each setting thereof comprising a control member mounted for turning movement and having a deep "carrying" notch and a shallow notch communicating with said deep notch, an oscillatory working pawl for actuating said wheels having a tooth coacting with said control member and always engaging in one of the said notches therein, the working pawl being held in inoperative relation to said wheels whenever the said tooth engages said shallow notch, and being in operative relation to the wheels when such tooth engages said deep notch, said control mechanism including means whereby when the machine is in its "repeat" setting said tooth will engage only the shallow notch of said control member in each actuation of the machine, when the machine is in its "consecutive" setting, said tooth will engage the deep notch of said control member in each actuation of the machine, and when the machine is in its "duplicate" setting, such tooth will engage said deep notch only in every other actuation of the machine.

28. In a numbering machine adapted for actuation in a plurality of settings, a series of type wheels, pawl means for actuating said wheels, means for controlling the operation

of the machine in its different settings comprising a ratchet mounted for turning movement in either direction and adapted to coact with said pawl means, and a retaining pawl for said ratchet, said ratchet being adapted when turned in one direction, to effect movement of said retaining pawl out of operative engagement with itself and when turned in the other direction to effect operative engagement of such pawl with itself.

29. In a numbering machine adapted for actuation in a plurality of settings, a series of type wheels, oscillatory pawl means for actuating said wheels, means for controlling the operation of the machine in its different settings comprising a rotatably mounted ratchet member adapted to coact with said pawl means, resilient means tending to turn said ratchet member in the one direction, a retaining pawl adapted to engage said ratchet member to limit the movement thereof in such direction, said pawl means being adapted to move said ratchet member in the other direction, the ratchet member having means adapted when such member is moved sufficiently in the said other direction to move said retaining pawl from operative engagement with itself, and means operable by the ratchet member upon sufficient movement of the latter in the said one direction and adapted to effect operative engagement of the retaining pawl with such ratchet member.

30. In a numbering machine, a series of numbering wheels, an oscillatory barrel on which said wheels are mounted, and means mounted on and movable with said barrel for advancing said wheels to effect changes in the numbers set up thereby.

31. In a numbering machine, a series of numbering wheels, pawl means adapted to move said wheels to effect changes in the numbers set up thereby, and means for actuating said pawl means comprising an oscillatory barrel on which said wheels and said pawl means are mounted.

This specification signed this 29th day of December, 1927.

WILLIAM F. HAUPT.
